UNITED STATES PATENT OFFICE.

ROBLEY C. MILLARD, OF ATLANTA, GEORGIA.

SAFETY APPLIANCE FOR RAILWAY-TRAINS.

1,181,332.

Specification of Letters Patent.

Patented May 2, 1916.

Application filed February 6, 1913. Serial No. 746,650.

To all whom it may concern:

Be it known that I, ROBLEY C. MILLARD, citizen of the United States, residing at Atlanta, in the county of Fulton and State of Georgia, have invented certain new and useful Improvements in Safety Appliances for Railway-Trains, of which the following is a specification.

My invention relates to new and useful improvements in automatic safety appliances for railway trains and more particularly to that type in which the railway system is divided into blocks or sections and in which each locomotive employed upon the system is provided with an apparatus adapted to co-act with a similar apparatus upon another locomotive, if in the same block, to close circuits through both locomotives and vent the main air line pipe of both locomotives to apply the air brakes and stop the trains.

More specifically my invention is an improvement over the apparatus set forth in and covered by Letters Patent No. 882,157, granted to me March 17, 1908, the chief object of my invention being to simplify and render more efficient the construction set forth in said patent.

A further object of my invention is to provide an appliance of the character above set forth which will include but one manually operable switch in place of the two required in my previous patent and in which this switch is so arranged as to be automatically thrown to normal position upon the passage of either train out of the block.

A further object of my invention is to so arrange the mechanism of my appliance that the electromagnets employed in venting the air line may be employed only in opening and closing a small two-way valve, which may be operated with great ease because of its size and through which, when opened, a small amount of air from the air line will pass to a cylinder to actuate a plunger which in turn opens a relatively large valve in the air line to vent the same and apply the brakes, the pressure of the air in the air line being itself used to assist in the venting of the line.

A further object of my invention is to so wire the apparatus that a blue or other colored light will be kept burning at

all times to indicate that the batteries or other source of energy and the wiring are in good condition and in which a red or other colored light will be lighted and will remain lighted at all times when two or more trains are in the same block.

A further object of my invention is to provide means for telephonic communication between two or more trains in the same block, portions of the electro-magnet energizing circuits being employed as telephone circuits. And a still further object of my invention is to so arrange the switches along the railway system that an open switch in any block will have the same effect upon a train entering the block that a second train in the block would have.

With these and other objects in view, my invention will be more fully described, illustrated in the accompanying drawings, and then specifically pointed out in the claims which are attached to and form a part of this application.

In the drawings: Figure 1 is a diagrammatic view of a section of railway track, showing two locomotives traveling in the same direction and in the same block, the valves and the electric means for controlling said valves being shown in operation to vent the air brake lines of the train; Fig. 2 is a similar view again showing two trains in the block, but showing the manually operated switches in the reverse position to close the valves of the air brake lines and permit the continued movement of the trains; Fig. 3 is a detail view of the trolley carried by each locomotive and forming part of the valve operating circuits; Fig. 4 is a front elevation, partially in section, of the valves and valve operating mechanism of one of the locomotives, this mechanism being identical in all locomotives, the valves being shown in closed position as in ordinary use; Fig. 5 is a view similar to that shown in Fig. 4, but with the valves open, the position of the mechanism there being the same as that shown in Fig. 1.

Corresponding and like parts are referred to in the following description and indicated in all the views of the drawings by the same reference characters.

To insure a clear understanding of the appliance and the manner of operation, it will

first be necessary to describe the railway track over which the locomotives or trains pass. This track, shown at 10, is of the usual type, the rails being electrically bonded in the customary way to admit of their use as return conductors, with the exception of the provision of a third rail 11. This rail may be as light as desired, or in fact may be nothing more than a wire as it merely serves as an electric conductor between the appliances of the locomotives. At spaced intervals, usually one mile, the rails forming the third rail 11 are separated slightly from each other and insulated as shown at 12 to prevent the passage of current from one rail section to another and also prevent the formation of a gap which would cause a trolley or brush, hereafter to be described, to jump. The rails making up this third rail, with the exception of these breaks, are electrically bonded so that the rail sections between adjacent breaks 12 each form a continuous conductor.

Each locomotive equipped with my appliance is provided with a trolley, brush or other suitable device 13 adapted for travel along the third rail 11 and so mounted that it may be raised or lowered by the engineer, fireman or other operator on the locomotive or the train drawn thereby. This brush is so mounted as to be completely insulated from the locomotive for a reason which will be hereinafter apparent. At this point it might be well to state that inasmuch as the locomotive is the one essential of a train, and inasmuch as the entire travel of the train is governed by the engineer from the locomotive, my safety appliance, including the brush above described, is in each instance preferably mounted in the locomotive. As the mechanism and wiring of this appliance is identical in all locomotives, a description of the mechanism in one will suffice for all. In order to clearly understand the wiring and operation of the system a description of the mechanical means actuated by the closing of the circuits is necessary and attention is therefore directed to Figs. 4 and 5 of the drawings. In these drawings, as clearly shown, the entire mechanism, with the exception of the manually operable switch and the signal light, is inclosed in a casing 14 to protect it from dust and dirt and the front of this casing is usually closed by a glass plate, not shown, in order to permit a clear unobstructed view of the mechanism. One end of the pipe 15 of the air brake pipe line is let into the upper portion of this casing and connected by any suitable coupling with a T 16. A pipe 17 leads from this T to a valve 18 and a pipe 19 leads from this valve through the lower portion of the casing, said latter pipe being open at its end. The valve 18 may be opened and closed by a partial rotation of

its valve stem 20, the free end of which is provided with angularly formed faces to seat in an angular socket formed in one end of an operating lever 21. A pipe 22 leads from the branch of the T 16 to a two-way valve 23 which may be opened and closed by reciprocating a valve stem 24 having spaced collars 25 adjacent its free end, this pipe 22 and its valve 23 being supported in place by a bracket 26 secured to the rear wall of the casing.

A pipe 27 leads from the outlet port of the valve 23 to the lower end of a vertically disposed cylinder 28 mounted upon a bracket 29 carried by the casing. This cylinder is provided with a gas tight piston 30, the piston rod 31 of which extends through a cap 32 of the cylinder and terminates in spaced ears 33.

A bell crank lever 34 is pivotally mounted intermediate its length as at 35 upon a downwardly depending bracket 36 carried by the top of the casing and one arm 37 of this lever extends between the ears 33 of the piston, being pivoted thereto by a pivot pin 38. The free end of this arm 37 is provided with a plurality of spaced perforations 39 and a weight 40 is slidably mounted on the arm and adjustably secured in place by a bolt or pin 41 passed through the weight and one of the perforations 39. A link 42 is pivotally connected by one end to the opposite arm of the lever 34 and by its other end to the free end of the lever arm 21 employed in opening and closing the valve 18.

Assuming that the air brake pipe is closed as in ordinary service, air being maintained under pressure therein, and that the valves 18 and 23 are both closed, it will be apparent that if the valve stem 25 is drawn outwardly to open the valve 23, air will pass, under pressure, from the air line pipe 15 through the pipe 22, valve 23 and pipe 27 to the cylinder 28. The pressure of this air in the cylinder 28 will raise the piston 30 to rock the bell crank lever 34 and through the link 42 actuate the lever 21 to open the valve 18 when the air brake line pipe 15 will be vented through the valve 18 and pipe 19 to apply the brakes on the train. It will further be apparent that the cylinder 28 and piston 30 also serve as a dash pot to act, in connection with the adjustable weight 40, to cause a gradual opening of the valve 18 rather than a sudden opening and so permit a gradual application of the brakes.

As a means for actuating the valve stem 24, I provide oppositely disposed electromagnets 43 and 44, the former of which is mounted upon a bracket 45 carried by the casing and the latter of which is mounted upon the bracket 26 supporting the pipe 22, these magnets being mounted with their poles in spaced relation for co-operation with

5 a common armature 46 pivoted as at 47 upon a bracket carried by the casing. The free end of this armature is slotted as at 48 to engage the valve stem 24 between the 10 collars 25 and these collars are so spaced upon the valve stem that when the armature 46 is attracted by the magnet 43, it will engage the outermost collar to move the valve to open position, while when attracted by 15 the magnet 44, it will engage against the other collar to close the valve.

20 In connection with the wiring of the device, I employ a peculiar form of switch which is preferably mounted upon the outside of the casing and which includes a base 49 of insulating material having spaced contacts 50 and 51 and a swingingly mounted switch blade 52 having an arm 53 adapted to engage the contact 50 in one position and the contact 51 in the opposite position, this switch blade being normally held in engagement with the contact 50 by a spring 54 and a stop pin 55. An electro-magnet 56 is mounted upon the base 49 in position, when 25 energized, to hold the switch blade 52 in engagement with the contact 51. The operation of this switch, including the wiring of its contacts and magnet, will be more fully explained in connection with the wiring of 30 the system proper and any further description of the same is, at present, unnecessary.

35 Incandescent light sockets 57 and 58 are mounted upon the top of the casing or at any other suitable point and carry incandescent bulbs 59 and 60, these bulbs being of different colors, the bulb 59 being preferably blue, while the bulb 60 is preferably red.

40 Having thus described the mechanical portion of my safety appliance, I will now describe the various circuits by means of which the valves 23 and 18 are opened and closed through the energization of the magnets 43 and 44. Referring particularly to Figs. 1 and 2 of the drawings, it will be 45 noted that in each instance I have illustrated the safety appliances upon two locomotives both included in the same block, one of the locomotives with its safety appliance being shown at A, while the other is shown at B. 50 As the wiring of both A and B is identical, a description of the wiring of one of the appliances will be sufficient.

55 A locomotive, conventionally shown at 61 carries the brush or trolley 13 as previously described and one of its wheels 62 is electrically connected as by a wire 63 with one pole of a battery 64 or with any other source of electrical energy. A wire 65 connects the other pole of this battery with one contact 66 of a double knife blade switch 67, while a wire 68 connects the corresponding contact 69 of the switch 67 with the trolley or brush 13.

65 A wire 70 connects one of the knife blade terminals 71 with one terminal of the elec-

tro-magnet 44, while a wire 72 connects one terminal 73 of the opposite switch blade with the switch blade 52. A wire 74 joins the contact 51 of the switch 52 with the electro-magnet 56 and a wire 75 leads from the opposite terminal of the electro-magnet 56 to the free terminal of the electro-magnet 44. A wire 76 leads from the contact 50 of the switch 52 to one terminal of the electro-magnet 43 and a wire 77 leads from the opposite terminal of the magnet 43 to the wire 70.

70 A conductor wire 78 leads from the wire 70 preferably at the point of juncture of said wire and the wire 77 to one binding post of the electric light socket 38 and a wire 79 leads from the other binding post of said light socket to the wire 72. A conductor wire 80 leads from the wire 63 to one binding post of the electric lamp socket 57 85 and a wire 81 leads from the other binding post of said lamp socket to the wire 65, these wires forming a continuous circuit through the battery and light 59. A telephone instrument of the portable type, conventionally shown at 82 is connected by the wires 83 and 84 with the wires 68 and 65, respectively.

90 The operation of the above described device is practically the same as that of the device covered in my previous patent before referred to and but slight description of the same is therefore necessary. It will of course be apparent that the lamp 59 in each device is always burning to show that 100 the batteries are in working order. Further the switches 52 are normally in the position shown in Fig. 1 of the drawings. The switches 67 are at all times kept closed, being incorporated merely as an alternate 105 means for rendering the entire device inoperative. They are not necessary however, as the trolley or brush 13, if raised, will accomplish the same purpose as the opening of the switch 67, the said switch being 110 therefore provided merely for convenience.

115 Each train will be equipped with a battery of a different strength from the batteries of all other trains which are to operate over the same track in order that, in instances when the battery of one train would be acting against that of the other, the system may still be operative.

120 Assuming that two trains enter the same block, as shown in Fig. 1 of the drawings, a circuit will be formed from the battery 64 of train A, through the wire 63 and wheel 62 of said train to the rail 10 of the track and through this rail to the wheel 62 of the train B, then through the wire 63 of said train, battery 64, wire 65, switch 67, wire 72, switch blade 52, wire 76, electro-magnet 43, wire 70, switch 67, wire 68 and brush 13 of train B to the third rail 11, through said third rail to the brush 13 of train A, 130

wire 68, switch 67, wire 70, wire 77, electro-magnet 43 of train A, wire 76, switch blade 52, wire 72, switch 67 and wire 65 of train A back to the battery 64. The closing of 5 this circuit energizes the electro-magnets 43 of both devices A and B and opens the valves 23 and 18 of each device to apply the brakes in both trains. At the time that this circuit is closed, a branch circuit is 10 formed in each device through the light 60 to give the danger signal to the engineer of each train. Furthermore, it will be apparent that the closing of this circuit, inasmuch as it is simultaneously closed 15 through both devices, throws the telephone instruments of the two trains into circuit with each other and the engineer of one train may readily converse with the engineer of the other and decide between them 20 which train shall proceed and in which direction.

As soon as either engineer decides to start his train, he swings the switch blade 52 into engagement with the contact 51 and 25 with the pole of the electro-magnet 56. This closes the circuit from the battery 64 of his train, which we will assume is train A, through the wire 63, wheel 62, rail 10, wheel 62 of train B, wire 63 and battery 30 64 of said train, through the wire 65, switch 67, wire 72, switch blade 52, wire 76, electro-magnet 43 of train B, wire 70, switch 67, wire 68 and brush 13 of train B, through the third rail 11, brush 13 35 of train A, wire 68, switch 67, wire 70, electro-magnet 44 of train A, wire 75, switch blade 52, wire 72, switch 67 and wire 65 back to the battery 64. It will be noted that this circuit passes through the electro- 40 magnet 56 and that this magnet is therefore energized to hold the switch blade 52 of train A in engagement with the contact 51 to keep this circuit closed until broken at some other point. This circuit draws the 45 armature 46 of train device A into engagement with the electro-magnet 44 to close the valves of said train and release the brake thus permitting the starting of the train. At the same time the valves of train 50 B are held open and said train cannot proceed unless its engineer also swings the switch blade 52 into engagement with the contact 51. If he does this, the same circuit as that above described, will be formed 55 with the exception that in train B the circuit instead of passing through the electro-magnet 43, as previously described, will, in this latter instance, pass through the electro-magnet 44 to close the valves of train B 60 and permit the starting of the train.

Branch circuits through the lights 60 of both train devices are formed by any of the above described circuits and it will be apparent that as long as two trains remain in 65 the same blocks, the red lights will continue

burning and the telephones will also continue to be in communication with each other. As soon, however, as either of the trains A or B passes from the block containing the other, the circuit between the 70 trains will be broken by the break in the third rail 11 occurring between the trains and this breaking of the circuit will deenergize the magnets 56 of both train devices to release the switch blades 52 which will immediately fly back to the normal position shown in Fig. 1 of the drawings. In other words, as soon as the trains pass into different blocks, their safety appliances are automatically returned to normal position to 80 act in case another train is already in the new block or in case another train enters immediately after them.

From the above description, it will be apparent that the appliance in either locomotive will be operated to apply the brakes of the locomotive and train to which it is attached whenever a circuit between the track 10 upon which the wheel 62 is moving and the third rail 11, is closed. It will therefore be apparent that the appliance may be employed to automatically stop trains in case of an open switch in the track which might otherwise derail the train by the provision of a contact electrically connected to the 95 third rail 11 and so positioned as to be engaged by the switch point of the rail 10 in case the latter is open.

In order to insure a clear understanding of such an arrangement, I have illustrated 100 an open switch 85 in Fig. 2 of the drawings, the rails 10 of the main line track being provided with swinging switch points 86 adapted to normally form with the adjacent rail a continuous main track but movable in the 105 position shown in Fig. 2 of the drawings to permit the passage of a train from the main track to a switch track, the rails of which are shown at 87. The rails of the main track 10 are bonded about these switch points, as shown at 88, and a contact 89 is placed in position to be engaged by the switch point of that rail over which the wheel 62 passes whenever said switch point 110 is in open or partially open position. This contact is electrically connected by a wire or other suitable conductor 90 with the third rail 11 of the track. In operation, whenever this switch point is in partially open or open position and a locomotive equipped with 115 one of my appliances, enters the block containing the switch, a circuit is closed through the appliance to open the valves and apply the train brakes, this circuit being the same as the brake operating circuit previously described with the exception that instead of being closed through the appliance of a second locomotive it is closed through the bridge between the rails 10 and 11 formed 120 by the contact 89 and conductor 90.

It will of course be understood that either of the rails 10 may be employed as the conductor or both, as desired, and that in the latter case a wheel upon either side of the 5 engine will be electrically connected with the appliance carried thereby.

The telephone connected in the circuit is of great value, particularly in systems in which the switches are arranged to operate the 10 train brakes, due to the fact that without the telephone it would be impossible for the engineer to determine whether the block was rendered dangerous by the presence of a second train or by the presence of an open 15 switch, making it necessary for him to advance the train at an extremely slow rate under the apprehension that there was another train in the block, when as a matter of fact, the danger might be due to an open 20 switch one mile or even farther ahead and the location of which he knew.

It will of course be understood that I do not wish to limit myself to the details of construction and specific arrangement of 15 parts and circuits as various changes may be made at any time, within the scope of the appended claims, without in the slightest degree departing from the spirit of my invention.

30 Having thus described the invention, what is claimed as new is:

1. In railway safety appliances, the combination of a valve in the main pipe line controlling the brake mechanism, a second 35 valve connected with said line controlling the opening of the first, means for opening said second valve under abnormal conditions, means including a manually operable switch for closing said valve and holding 40 the same closed under the same abnormal conditions, and means operable to release said valve holding means to permit the free opening of the same upon a future occurrence of abnormal conditions.

45 2. In railway safety appliances, the combination with the main pipe line controlling the brake mechanism, of a valve in said pipe line arranged to vent the pipe line when open, a second valve connected with said 50 pipe line arranged upon opening to open the first, an armature movable in one direction to open said second valve and in the opposite direction to close it, and oppositely disposed electromagnets included in circuits 55 which are closed under abnormal conditions.

3. In railway safety appliances, the combination of a valve in the main pipe line controlling the brake mechanism, a second valve connected with said line, means operable by the opening of the second valve for 60 opening the first, and means for opening the second valve, said means including oppositely disposed electro-magnets, a common armature pivoted for movement from one 65 magnet to the other and operatively engag-

ing the second valve, and circuits normally open through said electro-magnets but adapted to be closed under abnormal conditions.

4. In railway safety appliances, the combination of a valve in the main pipe line of the brake mechanism, means for venting the pipe line upon the opening of said valve, a reciprocating valve stem for said valve, a swinging armature movable in one direction 75 to open the valve and in the opposite direction to close it, an electromagnet mounted upon either side of the armature, circuits for said electro-magnets, and a switch for selectively determining which of said circuits 80 shall be closed.

5. In railway safety appliances, the combination of a valve in the main pipe line of the brake mechanism, means for venting the pipe line upon the opening of said valve, a reciprocating valve stem for said valve, a 85 swinging armature movable in one direction to open the valve and in the opposite direction to close it, an electromagnet mounted upon either side of the armature, circuits for said electro-magnets, and a switch for selectively determining which of said circuits 90 shall be closed, said switch being normally held to permit the closing of one circuit, and means carried by the switch for holding the same to close the other circuit until the other circuit is broken at a point 95 exterior to the switch.

6. In a railway safety block system, the combination with a locomotive having a 100 main pipe line controlling the brake mechanism, of a valve controlling the venting of the pipe line, oppositely disposed electromagnets having a common armature movable in opposite directions to open and close 105 said valve, spaced contacts, electrical connection between each of said contacts and one of the magnets, a brush carried by the locomotive and engaging one of the rails, electrical connection between both magnets 110 and said trolley, a wheel on the locomotive having electrical contact with another rail and insulated from the brush, a switch blade movable into engagement with each of the contacts, and electrical connection between 115 said switch blade and the wheel.

7. In a railway safety block system, the combination with a locomotive having a main pipe line controlling the brake mechanism, of a valve controlling the venting of 120 the pipe line, oppositely disposed electromagnets having a common armature movable in opposite directions to open and close said valve, spaced contacts, electrical connection between each of said contacts and one of the magnets, a brush carried by the locomotive and engaging one of the rails, electrical connection between both magnets 125 and said brush, a wheel on the locomotive having electrical contact with another rail 130

and insulated from the brush, a switch blade movable into engagement with each of the contacts, electrical connection between said switch blade and the wheel, a telephone, 5 and electrical connection between the telephone and the connections between the magnets and rail and the switch blade and rail.

In testimony whereof I affix my signature in presence of two witnesses.
